UNITED STATES PATENT OFFICE

HARRY LEE VAN ZILE, OF NEW YORK, N. Y.

SUPERHEATER.

No. 852,640.

Specification of Letters Patent.

Patented May 7, 1907.

Application filed May 28, 1904. Serial No. 210,159.

To all whom it may concern.

Be it known that I, HARRY LEE VAN ZILE, a citizen of the United States of America, and a resident of the city, county, and State of New York, have invented certain new and useful Improvements in Superheaters, of which the following is a specification.

My invention relates to combined boilers and superheaters and method for operating the same.

The object of my invention is to provide a means for maintaining a supply of pure water for the purpose of flooding the superheater, and a convenient means for flooding the superheater with water and removing the water from the superheater and returning it to the reservoir.

My invention consists in providing, in combination with a boiler and superheater, a reservoir preferably located at an elevation above the superheater, in maintaining connections between the reservoir and the superheater, and between the boiler and the superheater in such a way that the boiler may be shut off from the superheater, and the reservoir put in communication therewith for the purpose of flooding the superheater and maintaining a water circulation therein, and such that the steam pressure from the boiler may be used to expel the water from the superheater back into the reservoir.

It consists further in providing connections between the reservoir and the steam space of the boiler whereby steam may be made to pass from the boiler to the reservoir and condense therein and thus maintain a supply of pure water, and in other novel features and constructions to be hereinafter more fully pointed out and described.

The economic advantages of using superheated steam for power purposes have long been well known and many forms of superheaters have been devised. The heating surface of a superheater to be effective must be so placed as to come in contact with high temperatures. During the normal operation of the superheater the steam passing through it absorbs sufficient heat to prevent injury to the superheater resulting from these temperatures. When, however, steam is being raised in the boiler, or when, from any other cause, there is no current of steam passing through the superheater, the superheater, unless flooded with water, will soon become dry and be rapidly destroyed by the intense heat surrounding it. To obviate this diffi-

culty numerous plans have been devised, by means of which, at such times, the superheater has been flooded with water from the boiler. It is well known, however, that a residue accumulates in the water in the boiler and forms a scale upon the boiler tubes which is very objectionable, and this scale upon the superheater tubes, which are subjected to a higher degree of heat, and which, on account of their being filled only with steam during the normal use of the superheater, causes them to acquire a much higher temperature than the regular tubes of the boiler which are in contact with water, and on this account is all the more objectionable and results in the rapid destruction of the superheater tubes.

The formation of scale on the heating surfaces of superheaters is at present one of the chief objections to their use. In my present invention I have provided means by which the superheater is efficiently protected by pure water.

In the drawings accompanying and forming part of this specification, Figure 1 represents a front view partially in section of a boiler and superheater embodying the preferred form of my invention; Fig. 2 represents a plan view of the same partially in section; Fig. 3 represents a side elevation partially in section, and Fig. 4 represents an enlarged partial section through a portion of the rear water-leg and superheater header.

I have chosen the well known water-tube type of boiler to illustrate my invention. It will be obvious, however, that many of its features are applicable to other forms.

The reference characters are used in the same sense in all of the drawings and the specification.

Numeral 1 represents the steam drum of the boiler.

2 and 3 represent, respectively, the front and rear water-legs which are connected by the usual water-tubes.

5 represents the tubes forming the heating surface of the superheater.

So far as many of the features of my invention are concerned the superheating surface may be in any convenient form. I prefer, however, to have the superheating surface formed, as illustrated in the drawings, of one or more rows of tubes 5 which replace or supplement one or more rows of water-tubes. The superheater tubes 5 pass directly through the front and rear water-legs, inside of hollow stays or tubes 6 which are made of appropri-

ate size, preferably to permit the superheater tubes to pass through them without making contact. The superheater tubes are expanded into the front and rear headers 7 and 8. The headers are provided with plugs or hand-hole plates 9 opposite the ends of the superheater tubes and they give convenient access to the interior of the tubes for the purpose of cleaning or renewing the same. The end of the front header 7 is connected to a branch 10, one end 11 of which leads to the pipe 12 communicating with the steam space of the boiler, while the other branch 13 leads to the reservoir 14 located outside of the boiler and preferably at an elevation above the superheater. The branches 11 and 13 are provided with valves 15 and 16, respectively. The end of the rear header 8 is connected with the T 17, one branch of which 20 communicates with the pipe 18 leading to the steam main, and is controlled by the valve 19, while the other branch is controlled by the valve 20 and leads through the pipe 21 to the water-reservoir 14. Between the valve 25 20 and the pipe 21 I prefer to employ a U tube or return-bend 22 for the purpose of forming a water-seal as will be hereinafter explained. The upper part of the water-reservoir 14 is connected with the steam space of the boiler by means of the pipe 23, communication through which is controlled by the valve 24. 25 is a safety valve on the drum 14. 26 is a water-gage, 27 is a pressure relief-valve, and 28 is a blow-off.

29 is a water-gage on the water-seal or return-bend 22.

30 is a pipe leading from the steam space of the boiler to the main, and communication through this pipe is controlled by the 40 valve 31.

The operation of my invention is as follows: Assume that the boiler is cold and that a fire is about to be started in the furnace; that the valves 16 and 20 are closed; that the superheater is empty, and that the reservoir 45 14 is about half filled with water, the amount of water being sufficient, however, to somewhat more than fill the superheater. Assume, also, that the valves 15, 19 and 31 are closed, and that the valve 24 is open. If, now, the valves 16 and 20 are opened the water from the reservoir 14 will run down into and fill the superheater; and when a fire is started in the furnace and the water in the 55 tubes 4 of the boiler, and the tubes 5 of the superheater, become heated, two independent circulations will be started, one in the boiler and one in the superheater. The valve 24, controlling communication through 60 the pipe 23, being open, will insure an equalization of pressure in the superheater and the boiler. None of the water, however, of the boiler circulation will be able to enter or mingle with the water in the superheater circulation. The superheater will, in fact, oper-

ate as an independent boiler. When the steam pressure has reached the required point and it is desired to superheat the steam, the valves 16 and 24 will be closed, the valve 15 opened, and the pressure-relief-valve 27 70 will also be opened. The opening of the pressure-relief-valve will relieve the pressure in the reservoir 14 and permit the pressure through the pipe 12 from the boiler to force the water down through and out of the superheater up into the reservoir 14, passing through the return-bend 22. The gage 29 will enable the operator to readily observe when all of the water has been withdrawn from the superheater. When this has occurred the valves 27 and 20 will be closed and the valve 19 opened to allow the steam to pass to the main through pipe 18. All of the steam will then pass from the steam space of the boiler through the pipe 12 and through 85 the superheater to the main. The amount of water in the reservoir 14 will be indicated by the water-gage 26, and by opening the valve 24, steam will pass from the steam space of the boiler into the drum and condense 90 therein, the drum being outside of the boiler and relatively cool. A supply of pure distilled water is thus added as required to keep the proper amount of water in the reservoir 14 for flooding the superheater. 95

In filling the reservoir 14 for the first time it is not necessary to use distilled water, as a single charge will not ordinarily contain enough impurities to form an appreciable scale on the tubes of the superheater. 100

It is of course obvious that after the superheater has been flooded and steam raised, the water in the superheater could be drawn off and allowed to escape, and an entire new charge condensed from the boiler in the reservoir. Inasmuch, however, as this would waste considerable water and heat and require considerable time, and especially, inasmuch as it might be necessary to shut the valve 19 and stop the flow of steam through the superheater before a sufficient amount of distilled water had been accumulated, I prefer to return the water from the superheater to the reservoir in the manner described. 110

The safety valve 25 is provided on the reservoir 14 for the contingency which might arise should the operator neglect to open the valve 24 when the valves 15 and 19 are closed during the raising of steam, as in this case an excessive and destructive pressure might be developed. 115

When steam is shut off by means of closing the valve 19 while the fire is still burning in the furnace, the valves 16 and 20 should be again opened to allow the water from the reservoir to again flood the superheater. 125

If the valve 24 is opened it will not be necessary to close the valve 15, as the pressure upon the water in the reservoir would be exactly equal to the pressure in the pipe 12 130

leading from the boiler. If, however, the valve 24 is closed while the superheater is flooded, it will be preferable to also close the valve 15, so that the development of steam at a more rapid rate in the superheater system than in the boiler may not be able to force the water from the superheater up through the pipe 12 into the boiler. Furthermore, I prefer to so proportion the heating surfaces of the boiler and of the superheater, with respect to the amount of water contained in the boiler and in the superheater, respectively, that steam will be generated at a more rapid rate in the boiler than in the superheater when the latter is flooded.

It will thus be seen that I have provided a rapid and convenient means for flooding the heating surfaces of the superheater with pure water, and with means for maintaining and replenishing the supply of pure water. It will also be seen that by this arrangement of the superheater tubes they are readily accessible for cleaning and removal and renewal without dismantling or disassembling any part of the boiler, and that the expansion and contraction of the superheater tubes may take place without disturbing or causing any strain whatever upon any parts of the boiler.

Having thus described my invention, what I claim is,—

1. The combination with a boiler and a superheater, of means for maintaining a supply of water out of liquid contact with the water of the boiler, means for flooding said superheater from said supply and returning the water from said superheater to said supply, without permitting it to mingle with the water of the boiler.

2. The combination with a boiler, of a superheater, valved steam connections between the steam space of the boiler and the superheater, a water-reservoir exterior to the boiler and means for flooding said superheater from said reservoir and returning water from said superheater to said reservoir.

3. The combination with a boiler and a superheater, of connections between the steam space of the boiler and the superheater of a reservoir, and means for producing a water circulation in said superheater and reservoir independent of the water circulation in said boiler.

4. The combination with a super-heater and valved inlet and outlet steam connections therefor, of a water reservoir and valved connections between said reservoir and the inlet and outlet ends respectively

of said super-heater, the inlet and outlet ends of said super-heater being arranged at different levels whereby the heating of said super-heater when flooded, will produce a water circulation in said super-heater and reservoir.

5. The combination with a boiler and a superheater, of a valved connection between the steam space of the boiler and the inlet end of the super-heater, a valved connection between the outlet end of the super-heater and the steam main, a water reservoir located above the super-heater, valved connections between said reservoir and the inlet and outlet ends respectively of said super-heater, one of said connections being provided with a U-bend to form a water seal.

6. The combination with a boiler and a super-heater, of a valved connection between the steam space of the boiler and the inlet end of the super-heater, a valved connection between the outlet end of the super-heater and the steam main, a water reservoir located above the super-heater, valved connections between said reservoir and the inlet and outlet ends respectively of said super-heater, one of said connections being provided with a U-bend to form a water seal, and a valved steam connection between the steam space of said boiler and said reservoir.

7. In a combined boiler and superheater, the combination with the front and rear water-legs and the water-tubes of a water-tube boiler, of superheater tubes between rows of water-tubes extending through said water-legs and connected to headers outside of said water-legs, a reservoir at an elevation above said superheater tubes, valved connections between said headers and said reservoir and valved steam connections between the steam space of said boiler and said super-heater.

8. If a flooding device for superheaters, the combination with inclined superheater tubes, of headers connected, respectively, to the upper and lower ends of the superheater tubes, a reservoir, valved connections between said reservoir and said headers, and a U tube or water-seal in the connections connecting the lower header with the reservoir.

In testimony whereof, I have signed my name to this specification in the presence of two subscribing witnesses.

HARRY LEE VAN ZILE.
